Wm Ettlinger's Design for Muff.

PATENTED JUL 11 1871

5104

Fig. 1

UNITED STATES PATENT OFFICE.

WILLIAM ETTINGER, OF NEW YORK, N. Y.

DESIGN FOR A MUFF.

Specification forming part of Design No. 5,104, dated July 11, 1871.

To all whom it may concern:

Be it known that I, WILLIAM ETTINGER, of the city, county, and State of New York, have invented a new and original Design for Muff; and I do hereby declare the following to be a full, clear, and exact description thereof, which will enable those skilled in the art to make and use the same, reference being had to the accompanying drawing forming part of this specification, in which drawing—

Figure 1 represents a front view of this muff. Fig. 2 is a rear view of the same.

Similar letters indicate corresponding parts.

This design relates to a muff with side wings projecting outward and upward, giving the upper edge of the muff an undulating form, whereby the same is readily distinguished from common muffs; and, furthermore, said side wings form protections for the wrists and lower parts of the arms of the person wearing my muff.

In the drawing, A designates the body of my muff, which is provided with side wings *a a*, giving to the upper edge *b* of the muff an undulating appearance. Said side wings are secured to the front of the muff, and they project beyond the inner edges *c c* of the hand-holes *d d*, (see Fig. 2,) so that, when the hands are inserted, the side wings form protectors for the wrists.

What I claim as new, and desire to secure by Letters Patent, is—

The design for a muff, as herein shown and described.

This specification signed by me this 12th day of June, 1871.

WM. ETTINGER.

Witnesses:

W. HAUFF,
E. F. KASTENHUBER.
